UNITED STATES PATENT OFFICE.

HENRY D. PELLE, OF STOCKTON, CALIFORNIA, ASSIGNOR OF ONE-HALF TO E. V. BURKE, OF STOCKTON, CALIFORNIA.

PIANO-ACTION-FLANGE HOLDER.

1,074,289.

Specification of Letters Patent. Patented Sept. 30, 1913.

Application filed February 24, 1913. Serial No. 750,192.

To all whom it may concern:

Be it known that I, HENRY D. PELLE, a citizen of the United States, a resident of Stockton, in the county of San Joaquin, State of California, have invented certain new and useful Improvements in Piano-Action-Flange Holders; and I do declare the following to be a full, clear, and exact description of the same, such as will enable others skilled in the art to which it appertains to make and use the same, reference being had to the accompanying drawings, and to the characters of reference marked thereon, which form a part of this application.

This invention relates to improvements in piano action mechanism and particularly to the means for maintaining in position the flanges upon which are flexibly mounted or hinged the numerous piano action parts. In the present style piano these flanges are all held in position by means of screws which require a great deal of time and patience to remove in order to take out the flanges when taking any of the parts of the piano out for the reason that the screws are usually in places very hard to get at. My improved structure involves a spring actuated retaining catch whereby said flanges may be taken out or put in at will in an easy and effective manner without the necessity of the use of such screws.

A further object of the invention is to produce a simple and inexpensive device, and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views.

Figure 1 is a side elevation of the complete piano action showing the use of my improved flanges. Fig. 2 is a perspective view of one of my improved flanges. Fig. 3 is a perspective view of a retaining box for my improved flanges. Fig. 4 is a fragmentary view of a retaining spring.

Referring now more particularly to the characters of reference on the drawings, 1 designates the piano key and 2 the exten-

sion piece, while 3 designates the lower rail and 4 a link between the lower rail flange and the member 2. This lower rail flange is one of my improved type and I will now describe the same, and this description will do as well for the several flanges in use on the upper rail 5, as shown in Fig. 1, but it will not be necessary to enter into a detailed description of each, as the use of the same in the several positions in the upper rail 5 will be obvious from the following description of the flanges as positioned in the lower rail 3.

In providing my improved structure I first insert a box or retaining member 6 in the lower rail 3, which member 6 is provided with a plurality of recesses or compartments 7 adapted to receive the flanges 8 having the usual projecting ears 9. In the side of each of the members 7 is cut a recess 10 to receive a corresponding pin 11 on each of the flanges 8. When the flanges are in position in the compartments 7, these pins 11 project into the recesses 10. I provide spring retaining members 12 having orifices 13 adapted to receive the said pins 11. This structure holds the flanges in the compartments 7 until it is desired to move the same. Then the spring retaining members 12 can be raised by means of upwardly projecting lips or curved portions "a," 85 which action will release said members 12 from the pins 11, the said lips or curved portions "a" forming a means by which the spring members may be grasped to perform the raising operation. Thereupon the flanges 8 can readily be taken out of the compartments 7 for any desired purposes. As heretofore stated, these flanges 9 have always been held in position by screws, and it can readily be seen that my improved structure would greatly lessen the time and energy necessary to remove or replace the flanges.

From the foregoing description it will readily appear that I have produced such a device as substantially fulfills the objects of the invention as set forth herein.

While this specification sets forth in detail the present and preferred construction of the device, still in practice such deviations from such detail may be resorted to as do not form a departure from the spirit of the invention.

Having thus described my invention what I claim as new and useful and desire to secure by Letters Patent is:—

1. In a piano action, a means for holding the flanges of said action, such means comprising a member provided with a plurality of compartments, such flanges being disposed in said compartments, and spring-retaining members to hold said flanges in position in said compartments, as described.
2. In a piano action, a means for holding the flanges of said action, such means comprising a member provided with a plurality of compartments, such flanges being disposed in said compartments, a pin on each of said flanges, and spring retaining members fitting over such pins, as described.

3. In a piano action, a means for holding the flanges of said action, such means comprising a member provided with a plurality of compartments, such flanges being disposed in said compartments, each compartment being provided with a recess in one of its sides, a pin on each flange, said pins fitting into said recesses, and spring retaining members fitting over said pins, as described.

In testimony whereof I affix my signature in presence of two witnesses.

HENRY D. PELLE.
